GOLF CLUB

Carl Wright, Geneva, Ohio, assignor to The American Fork & Hoe Company, Cleveland, Ohio, a corporation of Ohio

Application January 7, 1935, Serial No. 685

4 Claims. (Cl. 273—80)

This invention relates to golf clubs and particularly to golf clubs having metallic shafts.

In golf clubs of the class having metallic or tubular metallic shafts, the smaller diameter or head supporting end of the shaft is usually inserted into the bore of a thick walled tubular hosel of the club head; and it is desirable to prevent breakage at this point of the shaft and for various other reasons which will become apparent to those skilled in the art to effect a gradual merging of the outer surface of the relatively large diameter hosel end portion with the shaft at the small diameter portion thereof adjacent the end of the hosel.

It is an object of this invention therefore to provide an improved golf club of the metallic shaft class.

Another object is to provide, in a golf club of the class comprising a tubular metallic shaft inserted into a club head hosel, improved means for effecting a gradual merging together of the outer surface of the hosel and that of the shaft.

Another object is to provide an improved means for effecting the juncture of the head of a golf club with the metallic shaft thereof which will increase the durability thereof.

Another object is to provide means for joining the resilient metal shaft of a golf club to the head in an improved manner, to cause the flexure of the shaft in portions adjacent the head hosel to be distributed over a greater longitudinal extent of the shaft.

Another object is to provide an improved golf club shaft of tubular construction wherein the tendency to breakage heretofore prevalent in other shafts at or adjacent to the junction of the club head hosel to the shaft will be greatly lessened.

Another object is to provide an improved means for joining the hosel of a golf club head to a metallic shaft which will be presentable in appearance while at the same time having the advantage that it will function to distribute over a greater longitudinal extent of the shaft near the hosel the flexure thereof which results upon impact of the head with a ball.

Other objects will be apparent to those skilled in the art to which my invention appertains.

My invention is fully disclosed in the following description taken in connection with the accompanying drawing in which:

Fig. 1 is an elevational view of the golf shafts embodying my invention;

Fig. 2 is a fragmentary view showing in longitudinal section a part of the head end of the

club of Fig. 1, the view being to a larger scale; Fig. 3 is a fragmentary view similar to a part of Fig. 2 drawn to a still larger scale and illustrating the method of applying my invention to a golf club;

Figs. 4 and 5 are fragmentary views similar to Fig. 2, illustrating modifications.

Referring to the drawing, Figs. 1 and 2, I have shown at 1, the golf club shaft preferably tapering from a hand grip 2, at the large end of the shaft toward the club head 3 secured on the small end of the shaft.

The characteristics of the taper of the shaft constitute no essential parts of the present invention and in the embodiment illustrated, the shaft is step-tapered by the provision of short cylindrical sections 4—4 of successively smaller diameter proceeding toward the small end of the shaft, and the lower end portion 5 of the shaft is preferably gradually tapered and the shaft is secured to the head 3 by weldingly fitting or driving the tapering portion 5 into a corresponding tapering bore in the tubular hosel 6 of the club head 3 and secured against displacement therefrom by a transverse pin 7.

The upper end of the hosel 6 provides a transverse shoulder 8; and a ferrule construction shown generally at 9 is provided, disposed in telescopic relation with the shaft and abutting at its lower end as viewed in Fig. 2 upon the shoulder 8 and at its upper end secured to the shaft. This ferrule construction will now be described together with the method of making and assembling it in the club.

Before the tapering shaft portion 5 is wedgingly driven into the hosel 4 as above described, a ferrule portion 11 generally tubular in form and of metal, preferably brass, is telescoped over the lower end of the shaft portion 5 and moved along the shaft to a suitable distance from the shaft end at which the internal bore thereof fits the tapering shaft portion 5 and is then soldered or brazed or otherwise integrally permanently and rigidly secured to the shaft portion 5.

A ferrule portion 10 generally tubular and of metal preferably aluminum is then telescoped over the end of the shaft moved therealong until the upper end thereof abuts as at 12 with the lower end of the ferrule portion 11. The lower end portion 13 of the ferrule portion 11, over a substantial axial extent thereof, is cylindrical and of smaller diameter than the upper end of the hosel 6 or of the shoulder 8; and immediately above the cylindrical portion 13, the ferrule portion 10 is of abruptly increased diameter provid-

- ing a shoulder 14; and from the shoulder 14 to the extreme upper end 15 of the ferrule portion 11, the outer surface of both ferrule portions 10 and 11 is formed to provide a continuous unbroken frusto-conoidal surface outwardly concave and throughout of circular cross section. The upper end 15 of the ferrule portion 11 feathers out or merges without a shoulder into the outer surface of the shaft.
- 10 A sheath 16, preferably of celluloid or like material and of selected color, is fitted over the ferrule 9, the upper end thereof as at 17 extending beyond the upper end 15 of the ferrule portion 11 and closely fitting the shaft and covering the upper end of the ferrule portion 11, the lower end of the sheath 16 being constricted inwardly to fit around and under the shoulder 14 providing a celluloid shoulder 20, and to fit the cylindrical portion of reduced diameter 13 as shown at 18.
- 15 It is well known that sheath material such as celluloid may, by heating and forming or modeling processes, be formed as just described for the sheath 16, and inasmuch as such processes form no essential part of the present invention, the process of forming the sheath 16 need not be further described herein.
- 20 After the sheath 16 is applied as above described, a short cylindrical sleeve 19 of celluloid or the like and of selected color, preferably contrasting with the color of the sheath 16, is telescoped over the tubular portion 18 of the sheath.
- 25 After the ferrule 9, sheath 16 and sleeve 19 have been made and assembled as described above, the tapering shaft portion 5 is driven into the tapering bore of the hosel 6 and thereby the shoulder 8 of the hosel is rigidly abutted against the lower end of the ferrule portion 9, and also the sleeve 19 is compressed between the shoulder 8 and the shoulder 20 of the sheath 16 provided by forming the sheath material over the shoulder 14 of the ferrule. The pin 7 is then driven through the hosel and shaft end as described above.
- 30 When a golf shaft having the construction above described is used in play, and when upon impact of the head 3 with a ball the shaft bends in the portions of small diameter adjacent the head, such as in the tapering portion 5, a longitudinal upward thrust is exerted on the ferrule 9 by the shoulder 8 of the hosel; and in prior shafts where ferrules of one kind or another have been employed, the ferrule is shifted upwardly along the shaft; and where a finishing sleeve of celluloid or the like is employed or in 35 shafts wherein the ferrule itself is provided for the sake of improved appearance, the longitudinal shifting of the ferrule leaves an unsightly gap at the lower end of the ferrule or of the finishing sleeve thereof.
- 35 40 45 50 55 60 65 70 75 In the construction above described however, it will be clear that inasmuch as the ferrule is integrally joined to the shaft by the ferrule portion 11 the ferrule cannot shift along the shaft; and by continuing the sheath 16 by its portion 18 into the sleeve 19, and by rigidly clamping the ends of the sleeve 19 upon the shoulder 20 of the sheath, upon bending or flexing of the shaft cannot, even after long continued use, separate from the sleeve 19 nor develop an unsightly gap thereat or at the juncture of the sleeve 19 with the hosel shoulder 8.
- 75 Furthermore, by integrally joining the upper end of the ferrule 9 by its portion 11 to the shaft and by abutting the hosel upper end shoulder 8

on the lower end of the ferrule, and by gradually tapering the wall thickness of the ferrule upwardly and immersing it into the shaft outer surface, the relatively abrupt flexure which usually occurs in prior shafts close to the juncture of the hosel and shaft when striking a ball, and the reactive flexure thereafter, will be distributed over a substantially greater length of the lower end portion of the shaft and will not be concentrated in a small length of the shaft near the 10 hosel; and the shaft in its portion of smallest diameter will be caused to bend on a relatively large so-called radius of curvature, thereby reducing the liability of the shaft to break in the small diameter portion just above the hosel even after 15 long continued use; also the increased so-called radius of curvature effected by the described structure effects a longer contact between the head and the struck ball, providing greater length of flight and better direction.

20 To provide the ferrule portions 10 and 11 of the form and other characteristics above referred to, I preferably proceed by the process illustrated in Fig. 3. The upper ferrule portion 11 is made initially in the form of a tube having a 25 relatively thick wall from end to end and in this form is telescoped over the shaft and soldered or brazed in place as shown at 11a Fig. 3. The ferrule portion 10 is then telescoped over the shaft and is more in the form shown at 11a Fig. 3, 30 the outer surface thereof being more truly conical than the final form to be provided. The two ferrule portions 10a and 11a are then ground or otherwise reduced in diameter along the surface indicated at 21 in dotted line, the upper 35 end of the ferrule portion 11a being substantially ground away in order to feather it out and merge it into the surface of the shaft and the two ferrule portions 11a and 10a being simultaneously ground to join each other on an unbroken surface.

40 In the modification of Fig. 4, the upper end of the hosel 6 is provided with a shallow recess upon the bottom 22 of which the lower end of the cylindrical portion 13 of the ferrule abuts. The 45 cylindrical surface of the cylindrical portion 13 fits in the side wall 23 of the recess. A thin or short sleeve or washer 24 is clamped between the extreme upper end 8 of the hosel and the shoulder 20 of the sleeve 16. By this construction the ferrule is centered with respect to the hosel and an axially shorter sleeve 24 may be provided for the sake of appearance if desired.

45 In the modification of Fig. 5, the lower end of the sheath 16a terminates after it is turned 50 around the shoulder 14 of the ferrule portion 10; and the cylindrical portion 13 of the ferrule portion 10 is seated in a recess in the hosel end, as in the form of Fig. 4; a relatively thin washer 55 is disposed between the extreme upper end 60 of shoulder 8 of the hosel 6 and the shoulder 26 of the sheath 16a where it bends around the shoulder 14 and is clamped therebetween.

55 60 65 70 75 The mode of operation of the forms of Figs. 4 and 5 will be substantially the same as that of the form of Fig. 2.

In the several embodiments of my invention above described, the sheath 16 or 16a is illustrated as terminating above the brass ferrule portion 11. If preferred, the sheath may extend 70 all the way up to the large end of the shaft, or to the hand grip 2 thereon. Such a sheath is indicated in broken lines at 16b in Fig. 5.

75 It will be understood that in many respects the embodiment of my invention illustrated and de-

scribed may be modified without departing from the spirit thereof or sacrificing the advantages thereof and without departing from the scope of the appended claims.

5 I claim:

1. In a golf club, a shaft, a head secured to the shaft, a generally tubular metal ferrule telescoped with and substantially fitting the shaft, the ferrule being in two parts abutting end to end, one part abutting at an end portion thereof with a portion of the head and being of light weight metal such as aluminum and the other part of the ferrule being of brass or like material and soldered, brazed or the like to the shaft at a point remote from the head, and the head abutting ferrule part being sufficiently rigid to substantially increase the resistance of the shaft portion enclosed thereby to flexing stresses.
2. In a golf club, a head comprising a tubular hosel, a metal shaft secured in the hosel, a generally tubular ferrule on the shaft adjacent the head, comprising two parts abutting end to end, one part being of relatively thick walled tubular form and of light weight metal such as aluminum and abutting at an end portion upon an end portion of the hosel, the other part being of

relatively thin wall tubular form composed of brass or the like, soldered or brazed or the like to the metal of the shaft.

3. In a golf club, a shaft, a head secured to the shaft a generally tubular metal ferrule telescoped with and substantially fitting the shaft, the ferrule being of two parts abutting end to end, one part being of light weight metal such as aluminum and the other part being of a heavier weight metal such as brass or like material, which heavier metal is secured by soldering, brazing, or the like, to the shaft.

4. In a golf club, a shaft, a head secured to the shaft, a generally tubular metal ferrule telescoped with and substantially fitting the shaft, the ferrule being of two parts abutting end to end, one part being of light weight metal such as aluminum and the other part being of a heavier weight metal such as brass or like material, which heavier metal is secured by soldering, brazing, or the like, to the shaft, a sheath adapted to be disposed over the ferrule, said ferrule being formed with a reduced shoulder portion which portion said sheath is formed to fit around and under.
